UNITED STATES PATENT OFFICE.

POVL T. LINDHARD, OF BROOKLYN, NEW YORK, ASSIGNOR TO F. L. SMITH & CO., OF NEW YORK, N. Y., A CORPORATION OF NEW JERSEY.

LINER FOR TUBE MILLS, ETC.

Application filed July 11, 1925. Serial No. 42,868.

Liners of silex, either of shaped blocks of the natural stone or of irregular pieces grouted in, were formerly employed almost exclusively for lining the shells or drums 5 of tube mills and ball mills and were generally satisfactory, except for variations in hardness, which necessitated renewal of portions of the lining. The difficulty in shaping the blocks of natural stone and variations 10 in the composite linings, together with the increasing difficulty in securing silex of uniform quality, the scarcity of the supply and the increasing cost have led to many efforts to produce substitutes for the silex 15 liners, cast metal liners being commonly provided and so formed as to prevent the charge of grinding bodies and of the material operated upon from slipping on the inner surface of the liners and, therefore, failing 20 of that degree of constant agitation which is necessary to secure the maximum of efficiency in a given mill. Most of such cast metal liners, as heretofore produced, quickly become smooth and permit the undesirable 25 slipping of the charge, or are otherwise subject to such wear that they quickly become broken, with the results that they must be replaced frequently and that there is excessive waste in the form of scrap. The 30 object of this invention is, therefore, to provide a liner which shall be capable of long continued use without becoming smooth and without requiring replacement at such a stage of wear as to involve excessive waste 35 in scrap. In accordance with the invention, the improved liner is made up of longitudinal bars of metal which, for convenience in manufacture and in application, are bridged in series so as to form liner blocks 40 of a size convenient for handling and application, the metal bars being separated (except for such bridges) by spaces which are filled with grout, by which also the bars or blocks are secured in place within the 45 shell or drum. To secure the most satisfactory result, the relative width of the grout filled spaces to the width of the bars is determined to some extent by the size and character of the grinding bodies with 50 which the mill is charged, the width of the grout filled spaces being such as to permit the cement grouting, when set, to be worn away by the conjoint action of the grinding bodies and the material being ground 55 at about the rate of wear as that to which

the deeper and harder metal bars are worn away, so that the longitudinally corrugated inner working surface of the liner is maintained throughout its use until the cement filling is almost completely worn away and 60 of the metal bars but little is left to become scrapped. The corrugated working surface is provided at the outset by providing metal bars of greater depth than the grouting and by sinking the grouting somewhat below the working surface of the bars. Preferably, also, the bars are formed at the 65 outset with somewhat rounded working surfaces, this characteristic being maintained throughout the wearing of the liner so that 70 agitation of the charge is kept up continuously in the operation of the mill and there is practically no slipping of the charge on the liner. The invention will be more fully explained hereinafter with reference 75 to the accompanying drawings in which it is illustrated, and in which:

Figure I is a face view of a series of bars cast in one block.

Figure II is a longitudinal section on the 80 plane indicated by the broken line 2—2 of Figure I.

Figure III is a transverse section on the 85 plane indicated by the broken line 3—3 of Figure I.

Figure IV is a transverse section showing several blocks or bars applied to the shell of a mill with the spaces filled with cement grout.

Figure V is a face view showing the placing 90 of the blocks in a mill so as to break joints.

Figure VI is a view in transverse section, on a larger scale than that of Figure IV, 95 illustrating the manner of coaction of cylindrical grinding bodies with the improved liner.

Longitudinal bars *a*, *a*, of a length convenient for handling and preferably having a rounded working surface *a*¹ and a 100 recessed rear surface *a*² for economy in production, are united by casting in a block for convenience in handling and in application to the shell of the mill, with a suitable curvature of the block, so as to leave 105 between successive bars longitudinal spaces *b*, *b*, which penetrate the block from face to back and are transverse to the direction of movement of the grinding bodies. The bars are united at intervals by bridges *c* which, 110

as shown in Figure II, preferably do not extend to the working of the block, but leave, in the front portion of the block, channels which extend continuously from end to end. Each 5 outer bar of the block is preferably formed, at its outer side, with spacing projections h so as to provide spaces between the adjacent bars of adjacent blocks.

When the blocks have been placed within 10 the shell d of the mill, cement grout f is forced into all of the spaces b between the bars and between the blocks and into the recesses c^2 in the blocks of the bars, so that when the cement has set the blocks are 15 surely held in place. In fitting the blocks to the mill one or more bars a may be split off as may be desired and wedges may be driven in between adjacent blocks to secure the same if necessary.

20 Preferably, the bars themselves and the spaces between them are of such widths as may be determined by the size and character of the grinding bodies employed. As shown in Figure VI, the short cylindrical 25 grinding bodies g are preferably employed and in that case and as also with grinding bodies of different shape, the bars have a width somewhat in excess of the greatest dimension of the grinding bodies and the 30 spaces between the bars have a width somewhat less than the minimum dimensions of the grinding bodies. The purpose of such 35 relation of dimensions is that in the operation of the mill, the relatively softer cement grout shall be worn away by the conjoint action of the grinding bodies and the material being ground at about the same rate as the metal bars a are worn away, whereby the longitudinally corrugated 40 working face of the liner is maintained until the cement grout is practically worn away and the bars are worn to such a thinness that they become liable to breakage.

In the foregoing description it has been 45 assumed that the bars a, a , are of cast metal and the filling in the spaces between such

bars of cement grout, but it will be obvious that such invention may be realized with other materials, the bars being of any suitable hard material and the filling between the bars of relatively softer material, whereby the corrugated working surface will be maintained as the liner wears.

I claim as my invention:

1. A liner block for tube mills, etc., consisting of a plurality of longitudinal bars of metal with rounded working surfaces, said blocks being provided with intervening spaces between the bars and bridge pieces connecting the bars at intervals along their 55 length.

2. A liner block for tube mills, etc., consisting of a plurality of longitudinal bars of metal with rounded working surfaces, said blocks being provided with intervening 60 spaces between the bars and bridge pieces connecting the bars at intervals along their length, the bridge pieces being recessed at the working face to form with the intervening 65 spaces continuous channels.

3. A liner for tube mills, etc., comprising blocks of longitudinal bars of metal with rounded working surfaces, said blocks being provided with intervening spaces and bridge pieces in each block connecting the bars 70 thereof at intervals along their length, and a filling of cement grout between the bars and sunk below the working surface of the bars.

4. A liner for tube mills, etc., comprising 75 blocks of longitudinal bars of metal with rounded working surfaces having a width as great as the minimum dimension of the grinding bodies and not greater than the maximum dimension thereof, and bridge 80 pieces connecting the bars at intervals along their length, and a filling of cement grout 85 between the bars and sunk below the working surface of the bars.

This specification signed this 9th day of 90 July, A. D. 1925.

POVL T. LINDHARD.
